Primary Examiner — Anhdao Doan

(57) **CLAIM**

The ornamental design for a benchtop sequencing device, as shown and described.

DESCRIPTION

FIG. 1 is a front perspective view of a benchtop sequencing device of our new design.

FIG. 2 is a front view of the benchtop sequencing device of FIG. 1.

FIG. 3 is a right side view of the benchtop sequencing device of FIG. 1; and,

FIG. 4 is a left side view of the benchtop sequencing device of FIG. 1.

The portions depicted in broken lines are not part of the claimed design.
